Primary Examiner — Mark A Goodwin(74) *Attorney, Agent, or Firm* — Klintworth & Rozenblat IP LLP(57) **CLAIM**

The ornamental design for a divider, as shown and described.

DESCRIPTION

FIG. 1 is a perspective view of a divider according to our new design;

FIG. 2 is a first side elevational view thereof;

FIG. 3 is a second side elevational view thereof;

FIG. 4 is a first end elevational view thereof;

FIG. 5 is a second end elevational view thereof;

FIG. 6 is a first plan view thereof;

FIG. 7 is a second plan view thereof;

FIG. 8 is a perspective view of a divider according to another embodiment of our new design;

FIG. 9 is a first side elevational view thereof;

FIG. 10 is a second side elevational view thereof;

FIG. 11 is a first end elevational view thereof;

FIG. 12 is a second end elevational view thereof;

FIG. 13 is a first plan view thereof; and,

FIG. 14 is a second plan view thereof.

The dash lines depict environment subject matter that forms no part of the claimed design.
